United States Patent Office

Des. 230,006

Patented Jan. 22, 1974

230,006

CHAIN SAW

Rodney L. Guthrie, St. Anne, Richard W. Condon, Frankfort, and Roscoe Combs, Jr., Kankakee, Ill., assignors to Roper Corporation, Kankakee, Ill.

Filed May 31, 1972, Ser. No. 258,479

Term of patent 14 years

Int. Cl. D8—03

U.S. Cl. D8—65

FIG. 1 is a perspective view of a chain saw embodying our new design.

FIG. 2 is a front view thereof.

FIG. 3 is a left hand side view thereof.

FIG. 4 is a rear elevational view thereof.

FIG. 5 is a right hand side view thereof.

FIG. 6 is a top elevational view thereof.

We claim:

The ornamental design for a chain saw, as shown and described.
